UNITED STATES PATENT OFFICE.

RENÉ MARIE DE BELLEVAL, OF BEAUVAIS, FRANCE.

LOCK FOR FIRE-ARMS.

SPECIFICATION forming part of Letters Patent No. 308,241, dated November 18, 1884.

Application filed May 12, 1884. (No model.) Patented in France December 22, 1883, No. 159,308, and in Belgium February 28, 1884, No. 64,314.

To all whom it may concern:

Be it known that I, RENÉ MARIE DE BELLEVAL, Marquis de Liques, a resident of Beauvais, in the Republic of France, and a citizen of the said French Republic, have invented certain new and useful Improvements in Locks for Fire-Arms; and I do hereby declare that the following is a full, clear, and exact description of the same, which will enable others skilled in the art to which it appertains to make and use the same, reference being had to the accompanying drawings, which form a part of this specification, and in which—

15 Figure 1 is a side view of my improved gun-lock. Figs. 2 and 3 are detail views of detached parts of the same.

Similar letters of reference indicate corresponding parts in all the figures.

20 My invention has relation to that class of locks for fire-arms in which the hammer is released by the depression of a sliding bolt, going away with the usual trigger; and it consists in the improved construction and combination of parts of the same, as hereinafter more fully described and claimed.

In the accompanying drawings, the letter A indicates the lock-plate, B the hammer, and C the mainspring, which are all of the usual 30 construction and secured and arranged in the usual manner. The tumbler D has a forwardly-projecting arm, E, to the outer end of which the swivel F is pivoted, which swivel has the free end of the mainspring pivoted to it, and the lower segmental edge of the tumbler has the usual notches, G, which are engaged by the end of a sear, H, pivoted upon a sear-screw, I, and provided with a rearwardly-projecting arm, J, against the upper 40 side of which the sear-spring K bears, forcing the forward end of the sear against the edge of the tumbler. A trigger-lever, L, is pivoted upon a screw, M, near its rear end under the rearwardly-projecting-arm of the 45 sear, bearing with its shorter rear arm against the rear end of the said arm of the sear, and a trigger-bolt, N, slides in a perforation, O,

in a laterally-projecting lip, P, at the upper edge of the lock-plate, and has a laterally-projecting lug, Q, pivoted in a perforation, 50 R, in the forward end of the trigger-lever. The several parts of the lock are partly covered and secured upon their inner sides by the bridle S in the usual manner.

It will now be seen that when the hammer 55 has been cocked it may be released by pressing downward upon the trigger-bolt, which depresses the forward end of the trigger-lever, which again, in turn, will raise the rear arm of the sear by its raised rear end, and the rear 60 end of the sear being raised the forward end of the same will be disengaged from the notches in the tumbler, allowing the hammer to drop.

I am aware that in locks for cannon and 65 similar pieces of ordnance a horizontally-sliding firing bolt or pin has been retained by means of the hooked end of a lever engaging a projection upon the bolt, the other end of which lever might be depressed by a vertically-sliding bolt, thus releasing the firing pin or bolt, and I do not claim such construction broadly; but

I claim—
The combination of the hammer and tumbler, the sear bearing against the notched edge of the tumbler with its forward end, and having a rearwardly-projecting arm, a trigger-lever pivoted under the rear arm of the sear, and bearing with its rear end against 80 the same, and a trigger-bolt sliding up and down in the lock-casing, and having its lower end pivoted to the forward end of the trigger-lever, as and for the purpose shown and set forth.

In testimony that I claim the foregoing I have hereunto set my hand this 1st day of April, 1884.

RENÉ MARIE DE BELLEVAL,
Marquis de Liques.
